UNITED STATES PATENT OFFICE.

JACK MACARTNEY AND ARCHIE V. HAHN, OF LOS ANGELES, CALIFORNIA.

ACOUSTIC HORN.

Application filed December 26, 1924. Serial No. 758,086.

Our invention relates particularly to means for increasing the volume of sound waves reproduced by a radio or phonograph loud speaking unit, and an object of this invention is the provision of novel means for the reproduction of music and the human voice and other sounds received by radio, phonograph records, etc.

Another object is to provide a novel acoustic horn which forms in itself a neat appearing cabinet.

Another object is to provide a horn of a character set forth which is very compact without destroying or impairing the efficiency thereof. In other words, by our invention a small compact horn having a length of about eight inches is capable of producing as good results as a horn of the old style having a length of approximately twenty-four inches.

A further object of this invention is to provide a novel tone path in which the tone waves or sound vibrations are enabled to expand in a uniform progressively increasing path, thus giving ample volume without distortion of the sound.

A still further object is to provide a novel horn which is square in cross section, thus producing slight differences in the wave paths which produce slight harmonics and modulate the tone.

Other objects are cheapness of construction and ease of assembly.

Another object is to provide a novel construction whereby a horn of this character may be made from panels having contours formed by a moulding machine.

Other objects, advantages, and features of invention may appear from the accompanying drawing, the subjoined detailed description and the appended claims.

The accompanying drawing illustrates the invention in one of the forms we at present deem preferable.

Figure 1 is a side elevation of our horn.

Fig. 2 is a front view of the same.

Fig. 3 is a longitudinal sectional view of the same, indicated by line x^3 , Fig. 2.

Fig. 4 is a perspective view of one of the panels used to form the outer horn.

Fig. 5 is a section on line x^5 , Fig. 3.

Referring more particularly to the drawing our horn consists of a progressively increasing tone path which doubles back on itself and comprises three sound conduits, an inner horn 1, a secondary horn 2 surround-

ing the inner horn and in spaced relation thereto, and an outer horn 3 which forms the bell of the horn and in which both the inner and secondary horns are mounted, and said outer horn is in spaced relation to the secondary horn. The horns 2 and 3 are shown as rectangular in length and square in cross section and are described as such for the sake of brevity, but it is understood that the cross section of the horns may be a polygon having any number of sides. The secondary horn 2 has a pointed outer end which with the outwardly extending curve 5 of the outer horn 3 forms a bell for the horn which flares outwardly in an approved manner and prevents undue interference of the sound waves as they are emitted from the horn.

The horn 3, is formed of four rectangular panels 4, the inner surfaces of which taper towards the front, which in Fig. 3 is shown at the top, and are formed with an outwardly extending curve 5 at the front which forms the bell of the horn. The outer surfaces of the panels 4 are suitably decoratively cut so that when the plurality of panels forming the outer horn are assembled they form a pleasing cabinet appearance for the entire horn. It will be noted, and one of the advantages of my invention is, that the panels 4 are formed by moving them through an ordinary moulding machine. The panels are then cut to width and the longitudinal edges mitered as at 6 and fit together to form the completed horn. Although the horn 1 and block 15 are shown as separate pieces it is apparent that the same may be made in a single piece; and it may be said that the inner horn is mounted in the outer horn or in the rabbet 16 formed in the outer horn. The panels may be joined together by any suitable means, preferably by gluing. A grill 7 is mounted in a rabbet 8 formed at the front end of the horn 3.

The secondary horn is supported by the grill and is suspended within and in spaced relation to, the outer horn 3. A screw 9 extending through the grill 7 and into the top of the horn 2 secures the horn 2 in fixed relation to the horns 1 and 3. The rear or inner end of the horn 2 flares rearwardly and outwardly from the front of the horn and approaches the inner surface of the horn 3, thus constricting the passage at the lower end thereof.

The horn 2 is also square in cross section and is formed of substantially triangular panels 10. These panels are formed with their outer surfaces curving from the rear of the horn, outwardly and inwardly as at 11 to form a blunt point, and diverge at their lower ends as previously described.

A deflecting point 12 is mounted centrally within the horn 2 at the front thereof, and extends a slight distance into the horn 1. The point 12 is fitted into rabbets 12' formed in the panels 10 and is provided with curved surfaces which tend to curve over the front edge of the horn 1. The inner surfaces of the panels 10 are curved rearwardly and outwardly from the point 12 as at 13 to provide a smooth deflecting surface which will not distort or reflect the sound.

The horn 1 is not shown as formed of panels, but is preferably made of a single block of wood or other fibrous material through which a tapered round bore 14 extends. This bore diverges towards the front of the horn to form a progressively increasing tone path. The horn 1 has a reduced end 19 which is received in a bore centrally formed in a block 15, which rests in a rabbet 16 formed in the panels 4 at the rear end of the horn 3. The block 15 has its inner surface curved as at 17. The inner surface of the horn 3 is curved inwardly as at 18 to meet the curved surface 17 of block 15, to form a deflecting surface as will be further described.

A phone or speaker unit 20 of any well known construction is mounted at one end of the bore 14, and the leads 21 thereof extend through an opening 22 in the lower end of one of the panels 4. An adjusting screw 22 extends through the rear closure 23 which is mounted in rabbets 24 formed in the panels 4 at the rear outside end thereof. The unit 20 preferably has a nipple 20' which fits into the bore 14 and retains the unit in assembled position.

The tone or sound waves emitted by the speaker unit 20 travel forwardly in the bore 14, and at the front thereof the tone waves are deflected and split by the tip 12 and surfaces 13, in four or more directions, depending on the number of sides in the horn 2. The sound then travels rearwardly along the diverging path 25 formed between the horns 1 and 2 is again deflected and split in four or more reverse directions by the surfaces 17 and 18 and the sound then travels frontwardly in the diverging passage 26 formed between the horns 2 and 3.

The sound in passing from the bore 14 into passage 25 passes through the curved entrance 27, which is formed by the front edge of the horn 1 and the diverging walls of the horn 2, and again in passing from the passage 25 to the passage 26 it passes through the curved entrance 28, which is

formed by the rear end of the horn 2 and the curved walls of the horns 1 and 3. This prevents a loud blast, and a consequent distortion of sound in the horn because the walls of the horn are so curved and spaced from each other that the area of the tone path constantly progressively increases.

The curvature of the walls along which the sound waves travel are such that there is a minimum amount of resistance and reflection. The inward curvature of the outer and front end of the horn 2, i. e., at the curves 11, leaves the bell of the horn or in other words the front or outer end of the horn 3 practically free of any obstructions and the sound waves pass outwardly from the horns without interference or damping.

Referring to Fig. 3 it will be noted that the outer free edge of horn 1 is closer to the inner surface of horn 2 than the inner free edge of horn 1 is to the point 12; and the inner rear surface of horn 2 is spaced a greater distance from horn 1 than the outer rear surface is spaced from horn 3. However, the diameter of the tone path in horn 2 around the outer edge of horn 1 being greater than that inside the horn 1 at this point does not require as great a cross sectional thickness to provide an increased area of tone path. The same is true at the inner end of horns 2 and 3. The tone path in each of the horns is so constructed, and especially at the deflecting or junction points of the horns, that it successively progressively increases in area from one end of the horn to the other. This construction reduces to a minimum distortion of the sound waves which distortion has been very noticeable heretofore in horns in which the tone path doubles back upon itself.

Our production is entirely formed of a fibrous material such as wood, and the horn 2 is suspended from the wooden grill 7, thus eliminating all harsh metallic sounds and vibrations.

By the foregoing construction it will be seen that the tone path doubles back upon itself and the sound waves are split in eight or more directions; and that the curves at the front of the horns 1, 2 and at the rear of the horns 2, 3 are such that the sound waves are not reflected back into the same passage but instead deflect the waves from horn 1 into horn 2 and from horn 2 into horn 3. By deflecting the waves without reflecting them we provide a horn which will not distort the sound.

We claim:

1. An acoustic horn comprising an inner horn, a second horn into which said inner horn extends, said second horn being formed of a plurality of panels, and an outer horn in spaced relation to said second horn, said outer horn being formed of a plurality of

panels, which when assembled form a cabinet inclosing the inner and second horn and forming therewith the entire horn.

2. An acoustic horn comprising an inner horn, a second horn into which said inner horn extends, said second horn being formed of a plurality of panels, and an outer horn in spaced relation to said second horn, said outer horn being formed of a plurality of panels which entirely inclose the inner and second horns and the panels of which said second and outer horns are formed being sections of molding.

3. In a device of the character set forth an inner horn, a second horn in spaced relation to said inner horn, an outer horn in spaced relation to said second horn, a grill over the end of said outer horn, and means to secure said second horn to said grill.

4. An acoustic horn comprising in combination an inner horn, a second horn in spaced relation to said inner horn, an outer horn in spaced relation to said second horn, a grill over the end of said outer horn, means to secure said second horn to said grill, said inner horn being secured to said outer horn and adapted to be provided with a phone unit mounted to extend into said inner horn.

5. An acoustic horn comprising an inner horn, a second horn in spaced relation to said inner horn; said second horn being square in cross section and formed of a plurality of sections of molding, an outer horn in spaced relation to said second horn said outer horn being square in cross section and formed of a plurality of sections of molding, means to support said inner horn and said second horn from said outer horn, and

adapted to be provided with a phone unit 40 extending into said inner horn.

6. An acoustic horn comprising an outer horn provided at one end with a block; an inner horn mounted in said block; a grill secured to the other end of said outer horn; a second horn encircling said inner horn and supported by said outer horn in spaced relation to said outer horn and to said inner horn; and a deflecting point in said second horn extending a slight distance into the 50 inner horn.

7. As an article of manufacture, rectangular panels having outwardly curved surfaces to form the bell of a horn and provided with rabbets; a block mounted in said rabbet; another block provided with a tapered bore and having a reduced end mounted in said first mentioned block; panels having curved surfaces to form with said rectangular panels and with said other block 60 a tone path; and a deflecting point mounted in the meeting point of said triangular shaped panels.

8. In a device of the character set forth, an inner horn, a second horn in spaced relation to said inner horn, an outer horn in spaced relation to said second horn, a grill inclosing the end of said outer horn, a screw element for securing said grill to said second horn, and a block secured to said outer horn 70 for supporting said inner horn in position centrally of said outer horn.

In testimony whereof, we have hereunto set our hands at Los Angeles, California, this 18th day of December, 1924.

JACK MACARTNEY.
